UNITED STATES PATENT OFFICE

ISACK GOLDBERG, OF NEW YORK, N. Y.

DESIGN FOR A SLIPPER

Application filed December 2, 1929. Serial No. 33,612. Term of patent 3½ years.

To all whom it may concern:

Be it known that I, ISACK GOLDBERG, a citizen of the United States, and a resident of New York city, county and State of New York, have invented a new, original, and ornamental Design for a Slipper, of which the following is a specification, reference being had to the accompanying drawing, forming part thereof.

The figure is a side perspective view of a slipper showing my new design.

I claim:

The ornamental design for a slipper, as shown.

ISACK GOLDBERG.
